SNOW SLED

Tsugio Ogata, Tokyo, Japan, assignor to Kabushiki Kaisha
Tokyo Gurafikkusu Dezainazu, Tokyo, Japan

Filed Oct. 23, 1968, Ser. No. 14,119

Claims priority, application Japan July 29, 1968

Term of patent 14 years

Int. Cl. D21—02

U.S. Cl. D34—15

FIG. 1

FIG. 2

FIG. 3

FIG. 4

FIG. 5

FIG. 6

FIG. 1 is a perspective view of a snow sled showing my novel design,

FIG. 2 is a top plan view thereof,

FIG. 3 is a bottom plan view thereof,

FIG. 4 is a front elevational view thereof,

FIG. 5 is a rear elevational view thereof, and

FIG. 6 is a right-hand elevational view thereof, the opposite side being a mirror image thereof.

The characterizing feature of my design is the particular configuration of the tubular seat support in combination with the tapered planar form of the seat as shown.

I claim:

The ornamental design for a snow sled, as shown and described.
